UNITED STATES PATENT OFFICE.

JAMES DODD, OF BRISBANE, QUEENSLAND, AUSTRALIA.

CASTING REEL.

Application filed September 13, 1926, Serial No. 135,153, and in Australia September 7, 1925.

This invention relates to improvements in casting and spinning reels which are attached to fishing rods, and upon which the line is wound and from which the line is cast.

The object of the invention is to provide improvements in casting reels whereby the turntable is easily manipulated, and in casting and spinning reels whereby a regulatable friction clutch mechanism is incorporated enabling a hooked fish, when suddenly or spasmodically exerting his strength against the winding in of the line, to expend his strength against such operation without 15 breaking the rod or line, which may be of comparatively light material.

In order that the invention may be better understood reference may be had to the accompanying drawings in which like reference letters refer to the same parts in the different figures.

Figure 1 is a sectional elevation of the casting reel in its position for casting;

Figure 2 is an end view looking at the 25 back of the reel;

Figure 3 is a detail view of the winding handle and hollow spindle;

Figure 4 is a detail view of the T-headed, threaded spindle;

Figure 5 is an edge view of one of the 30 discs;

Figure 6 is a face view of said disc;

Figure 7 is a detail view of the knurled nut;

Figure 8 is a vertical section of the turntable assembly and portions of the adjacent parts;

Figure 9 is a plan of the turntable housing;

Figure 10 is a plan of the turntable assembly in its housing.

In constructing a reel embodying this invention, I provide a back plate S having an integral hollow sleeve T and also provided 45 with a spring N and with a lug K which carries the turntable later described. At the top of the back plate S, I provide three holes respectively for pins upon which are mounted an eccentric W operated by a thumbscrew 50 on the outside of the backplate, a detent lever X, and a locking pin M which moves into or out of a hole K⁴ in an extension K³ of the turntable (see Figure 10). The locking pin M is guided by a lug Y, and Z is the 55 usual guide for the line.

The winding handle P (Figure 3) has a

hollow spindle P¹ adapted to accommodate itself in the hollow sleeve T, and is shouldered to stop the disc E and prevent it from contacting with the barrel C and thus cause 60 friction. In this winding handle P is also provided a recess adapted to accommodate a knurled nut A (see Figure 7).

The barrel C is provided with a boss H which is utilized as a brake drum. The boss 65 H is screw threaded and has a cap H¹. The barrel C has a central recess into which the hollow sleeve T on the back plate passes. On the other side of the barrel C is secured a toothed wheel C¹ for engagement by 70 detent X.

Inside the brake drum H, I place a disc E (see Figures 5 and 6), a split and bevelled ring G of fibre or the like and a disc F similar to disc E, the keys on the discs 75 E and F accommodating themselves in the keyways P² in the end of the hollow winding spindle P¹ and preventing circumferential movement of said discs.

The spindle D, which is provided with 80 a flat T-head, (see Figure 4) is passed into the hollow spindle P¹ and is screw threaded to take the knurled nut A.

In assembling the reel, the barrel C is placed in position on the hollow sleeve T 85 of the backplate S and then the hollow spindle P¹ is inserted into said sleeve. The disc E is placed in the hollow boss or brake drum H with the keys in the keyways P² and the bevelled side inward. The split 90 fibre ring G with its bevel inside is placed in the drum H and the other disc F placed over the hollow spindle P¹; its keys also being in the keyways P², and with its bevelled side facing the bevelled side of the 95 disc E. The T-headed bolt or spindle is passed into the hollow spindle P¹ and the knurled nut A is secured over it, thereby bringing the T-head into the keyway P².

When the T-head D is in position to hold 100 the discs E and F and the fibre ring G in place, the cap H¹ may be screwed over the brake drum H.

Referring to Figures 8, 9, and 10, the lug K on plate S is provided with a dove tail 105 recess adapted to accommodate a circular dove tail plate K¹ which is integral with the extension U for attachment of the reel to the rod in the usual manner. The extension K³ provided on the side of the turntable, as previously stated, has a hole K⁴ into which the locking pin M normally pro-

jects. A dove tail wedge piece V accommodates itself in the recess of lug K and is retained by screws K⁶.

In use, when it is desired to cast the line from the barrel, the locking pin M is pushed down against the spring N by means of the thumb piece L until the end of the locking pin M is out of engagement with the hole K⁴ in the extension K³. The back plate S may then be turned on the turntable until it is in the position shown in Figure 1. If it is desired not to use the checking means, the thumb screw on the eccentric W may be turned until the eccentric W forces the point of the detent X away from the toothed wheel C¹. After the line has been cast, the reel may be again brought to normal position by turning it on the turntable until the point of the locking pin M enters the hole K⁴.

Up to this point the braking mechanism may be left idle. The brake may be brought into operation by giving the knurled nut A a partial clockwise turn, thus tightening the flat T-head D against the bevelled disc F which in turn expands the bevelled split fibre ring G. The fibre ring is pressed outwards, between the discs E and F into contact with the wall of the brake drum H, the disc E being held against the shoulder on the spindle P¹ and against rotation by the keys in the keyway.

It will be obvious that the amount of friction desired is secured by the tightening of the knurled nut A, and further that although the spindle P¹ on the winding handle is turning clockwise in the hollow sleeve T, always without friction, the barrel C which carries the brake drum H and which fits over the sleeve T is governed by the friction set up by the fibre ring G through the discs E and F which are secured to the spindle P¹. Should the fish run out against the winding in of the line by the handle, the barrel may take an anticlockwise rotation but in opposition to the friction set up by the fibre ring in the brake drum, which ring may be held stationary by stopping the winding, or moved clockwise by continuing the winding.

It is found that very large fish may be landed without damage to the rod or line, which may be comparatively light, simply by adjusting the degree of friction and continuing to wind in until the fish is within reach of the gaff or landing net. A sudden run out by the fish only results in the barrel turning anticlockwise and preventing sudden strain without losing tension.

I claim—

1. In a fishing reel, a rotatable barrel; a carrier therefor; and a friction brake for controlling the rotation of the barrel comprising a drum fixed on said barrel, a pair of bevelled discs within the drum, a brake

ring interposed between the edges of said discs, and means for moving one disc toward the other to expand said ring outwardly into frictional engagement with the wall of the drum.

2. In a fishing reel, a rotatable barrel; a carrier therefor; and a friction brake for controlling the rotation of the barrel comprising a drum fixed on said barrel, a pair of bevelled discs within the drum, a brake ring interposed between the edges of said discs, a hollow winding spindle whereon the discs are keyed, a drawing spindle extending through the hollow spindle and having a terminal head which bears against the adjacent disc, and means for moving the second spindle endwise in one direction to force said adjacent disc toward the other disc and thereby expand the brake ring outwardly into frictional engagement with the wall of the drum.

3. A fishing reel, according to claim 1, in which the hollow spindle has a stop shoulder at one end against which one disc is disposed, while the drawing spindle head bears against the other disc; and in which a nut is rotatably carried by said hollow spindle at its other end for engagement with a threaded portion of the drawing spindle to effect the endwise movement of the latter when the nut is turned.

4. In a fishing reel, a rotatable barrel; a carrier therefor; means, including a turntable connection, for attaching the carrier to a fishing rod; a toothed wheel fixed on the barrel; a locking pin on the carrier for engagement with said turntable connection to prevent operation thereof; a detent on said carrier for engagement with said toothed wheel to hold the barrel against rotation; and a spring attached to said carrier and engaging the pin and detent at its opposite ends to maintain them in such engagement.

5. In a fishing reel, a rotatable barrel; a carrier therefor; a member for attaching the carrier to a fishing rod; a turntable connection between said member and carrier embodying a lug on the carrier having a recess therein, and a circular plate connected with said member and rotatably fitting in said recess; and a movable locking pin on the carrier to engage said plate and thereby hold the turntable connection against operation.

6. In a fishing reel, a carrier plate having a laterally-projecting sleeve; means, including a turntable connection, for attaching said plate to a fishing rod; a movable locking pin carried by said plate for releasable engagement with said turntable connection to hold it against operation; a barrel rotatably mounted on said sleeve; a fixed ratchet on said barrel; a detent pivoted to the plate and normally engaged with said ratchet to hold said barrel against rotation;

means for releasing said detent from such engagement; and a winding shaft mounted within said sleeve for rotating the barrel when released.

- 5 7. In a fishing reel, a carrier plate having a laterally-projecting sleeve; means, including a turntable connection, for attaching said plate to a fishing rod; a movable locking pin carried by said plate for releasable
10 engagement with said turntable connection to hold it against operation; a barrel rotatably mounted on said sleeve; a fixed

ratchet on said barrel; a detent pivoted to the plate and normally engaged with said ratchet to hold said barrel against rotation; means for releasing said detent from such engagement; a brake drum fixed to the barrel; a winding shaft mounted within said sleeve; and a friction clutch for releasably connecting said shaft with the brake drum. 15 20

In testimony whereof I have signed my name to this specification.

JAMES DODD.
